J. Vincent Martin

ATTORNEY.

UNITED STATES PATENT OFFICE

2,046,739

DRILL BIT

George G. Harrington, Houston, Tex., assignor to
 Reed Roller Bit Company, Houston, Tex., a
 corporation of Texas

Application June 6, 1933, Serial No. 674,510

13 Claims. (Cl. 255—71)

This invention relates generally to deep well drilling apparatus and specifically to roller bits. It has for its general object the provision of a new and improved bit having large cutters constructed and arranged to efficiently cut various hard formations.

A specific object of the invention is to provide a new and improved bit wherein the cutting action of spiral cutters can be most efficiently utilized.

Other objects will hereinafter appear.

The preferred embodiment of the invention is illustrated by the accompanying drawing, wherein Fig. 1 is a sectional elevation of the bit and Fig. 2 is a fragmentary elevation thereof.

In the drawing the bit head is indicated at 1. It has a threaded socket 2 for the reception of the conventional drill stem (not shown), by which the bit is rotated. Water is supplied to the cutters through the opening 3 in the head. The bit head has a pair of depending bearing projections 4 and 5 provided with downwardly opening slots 6 and 7 for the reception of the cutter pins 8 and 9. The cutter pin 8 extends to a position slightly past the longitudinal axis of the head 1 and is inwardly stepped as indicated at 10. It is to be understood that the cutter pin 8 may terminate in any expedient position desired adjacent the longitudinal axis of the head 1. The inner ends of the pins 8 and 9 are connected and spaced by the means indicated at 11, which includes an arm which may be integral with the pin 9, and a removable ring 12 fitted on the lug 13 of the arm 11 and surrounding the inner end of the pin 8. Upon the pins 8 and 9 are substantially frusto-conical spiral cutters 14 and 15, arranged with their base ends outermost. The cutters have longitudinal grooves 16 and 17 extending through the teeth 18 and 19. Between the cutters 14 and 15 and the bearings adjacent thereto may be interposed bearing washers 20 and 21.

The cutter pins and washers may be inserted in the bit head 1 as a unit and the ends of the pins 8 and 9 may then be secured in the slots 6 and 7 by welding.

It will be observed that the cutters are large so that the bearings therefor may also be made large and strong; that the area of contact between the cutters and the formation is relatively small but the cutters are arranged so that together they traverse an area equal to the area of the head. The advantages of these features will be apparent to those skilled in the art.

55 The invention is not limited to the specific

embodiment herein disclosed. Various changes may be made within the scope of the following claims. Of the many changes that may be made as to form without change in substance may be mentioned the construction of the cutter 14 in two pieces instead of one as shown.

I claim:

1. A rotary bit comprising a head and a pair of double spiral toothed substantially frusto-conical roller cutters rotatable on axes that are inclined upwardly and outwardly in substantially opposite directions substantially from the longitudinal axis of said head; said cutters being arranged with their base ends outermost; one of said cutters being arranged to traverse an area of substantially circular outline and of a radius extending from the longitudinal axis of said head to a point beyond the periphery of said head; and the other of said cutters being arranged to traverse an annular area of a width extending from a point substantially midway between the longitudinal axis of said head and the periphery of said head to a point beyond the periphery of said head; said cutters having a plurality of substantially longitudinal grooves extending substantially from end to end through the teeth thereof.

2. A rotary bit comprising a head and a pair of multiple spiral toothed substantially frusto-conical roller cutters rotatable on axes that are inclined upwardly and outwardly in substantially opposite directions substantially from the longitudinal axis of said head; said cutters being arranged with their base ends outermost; one of said cutters being arranged to traverse an area of substantially circular outline and of a radius extending from the longitudinal axis of said head to a point beyond the periphery of said head; and the other of said cutters being arranged to traverse an annular area of a width extending from a point substantially midway between the longitudinal axis of said head and the periphery of said head to a point beyond the periphery of said head; said cutters having a plurality of substantially longitudinal grooves extending substantially from end to end through the teeth thereof.

3. A rotary bit comprising a head and a pair of multiple spiral toothed substantially frusto-conical roller cutters rotatable on axes that are inclined upwardly and outwardly in substantially opposite directions substantially from the longitudinal axis of said head; said cutters being arranged with their base ends outermost; one of said cutters being arranged to traverse an area of substantially circular outline and of a radius extending from the longitudinal axis of said head to a point beyond the periphery of said head; and the other of said cutters being arranged to traverse an annular area of a width extending from a point substantially midway between the longitudinal axis of said head and the periphery of said head to a point beyond the periphery of said head; said cutters having a plurality of substantially longitudinal grooves extending substantially from end to end through the teeth thereof.

- of substantially circular outline and of a radius extending from the longitudinal axis of said head to a point beyond the periphery of said head; and the other of said cutters being arranged to traverse an annular area of a width extending from a point substantially midway between the longitudinal axis of said head and the periphery of said head to a point beyond the periphery of said head.
4. A rotary bit comprising a head and a pair of spiral toothed roller cutters rotatable on axes that are inclined upwardly and outwardly in substantially opposite directions substantially from the longitudinal axis of said head; one of said cutters being arranged to traverse an area of substantially circular outline and of a radius extending from the longitudinal axis of said head to a point beyond the periphery of said head; and the other of said cutters being arranged to traverse an annular area of a width extending from a point substantially midway between the longitudinal axis of said head and the periphery of said head to a point beyond the periphery of said head; said cutters having a plurality of substantially longitudinal grooves extending substantially from end to end through the teeth thereof.
5. A rotary bit comprising a head and a pair of spiral roller cutters rotatable on axes that are inclined upwardly and outwardly in substantially opposite directions substantially from the longitudinal axis of said head; one of said cutters being arranged to traverse an area of substantially circular outline and of a radius extending from the longitudinal axis of said head to a point beyond the periphery of said head; and the other of said cutters being arranged to traverse an annular area of a width extending from a point substantially midway between the longitudinal axis of said head and the periphery of said head to a point beyond the periphery of said head.
6. A rotary bit comprising a head having oppositely disposed depending projections; a pair of cutter pins supported by said projections and extending inwardly and downwardly therefrom substantially toward the longitudinal axis of said head; one of said pins extending substantially to the longitudinal axis of said head; means to connect and space the inner ends of said pins; and a substantially frusto-conical spiral cutter on each of said pins; said cutters being arranged with their base ends outermost to traverse an area substantially equal to the transverse area of said head.
7. A rotary bit comprising a head having oppositely disposed depending projections; a pair of cutter pins supported by said projections and extending inwardly and downwardly therefrom substantially toward the longitudinal axis of said head; one of said pins extending substantially to the longitudinal axis of said head; means to connect and space the inner ends of said pins; and a spiral cutter on each of said pins; said cutters being arranged to traverse an area substantially equal to the transverse area of said head.
8. A rotary bit comprising a head having op-

ositely disposed depending projections; a pair of pins extending from said projections downwardly and inwardly substantially toward the longitudinal axis of said head; one of said pins having an arm; and a ring on said arm and engaging the other of said pins to hold and space the adjacent ends of said pins; and roller cutters on said pins.

9. A rotary bit comprising a head, and a pair of spiral roller cutters mounted on said head, said cutters being on opposite sides of the longitudinal axis of said head and of unequal extent; one of said cutters having a right-hand spiral and the other of the said cutters having a left-hand spiral.

10. A rotary bit comprising a head, and a pair of spiral toothed roller cutters rotatable on axes that are inclined upwardly and outwardly from the longitudinal axis of said head; one of said cutters having a right-hand spiral and the other of said cutters having substantially longitudinal grooves extending through the teeth thereof.

11. A rotary bit comprising a head and a pair of spiral roller cutters rotatable on axes that are inclined upwardly and outwardly in substantially opposite directions substantially from the longitudinal axis of said head; one of said cutters being arranged to traverse an area substantially from the longitudinal axis of said head to a point beyond the periphery of said head; and the other of said cutters being arranged to traverse an area substantially from a point midway between the longitudinal axis of said head and the periphery of said head to a point beyond the periphery of said head; one of said cutters having a right-hand spiral and the other of said cutters having a left-hand spiral.

12. A rotary bit comprising a head and a pair of double spiral toothed substantially frusto-conical roller cutters rotatable on axes that are inclined upwardly and outwardly in substantially opposite directions substantially from the longitudinal axis of said head; said cutters being arranged with their base ends outermost; one of said cutters being arranged to traverse an area substantially from a point midway between the longitudinal axis of said head and the periphery of said head to a point beyond the periphery of said head; said cutters having a plurality of substantially longitudinal grooves extending substantially from end to end through the teeth thereof; one of said cutters having a right-hand spiral and the other of said cutters having a left-hand spiral.

13. A rotary bit comprising a head having oppositely disposed depending projections; a pair of pins extending from said projections downwardly and inwardly substantially toward the longitudinal axis of said head; separate means on one of said pins forming a depression receiving the other of said pins to hold in proper relative position the adjacent ends of said pins, and roller cutters on said pins.

GEORGE G. HARRINGTON. 65
